SECTIONAL PLUMB AND LEVEL

Filed Aug. 8, 1944

UNITED STATES PATENT OFFICE

2,383,166

SECTIONAL PLUMB AND LEVEL

Theodore F. Seiwell, Washington, D. C.

Application August 8, 1944, Serial No. 548,519

5 Claims.

(Cl. 287—9)

My invention relates to the general class of implements designed for use by carpenters and brick layers, with particular reference to a combined level and plumb of that type which is made up of several joined sections adapted to be disconnected for convenience in carrying the same as well as for the use of any one of the sections independently.

The principal object of my invention is to provide a particular form of lap-joint and securing means therefor whereby to hold the sections of the plumb and level firmly together in line with each other for use of the implement in this form, and in which the sections may be easily disconnected by simply pulling them apart longitudinally to release the securing means.

A further object of my invention is to include in the particular construction of lap joint means by which adjustment is permitted to take up for wear or looseness which may occur between the sections in the use of the implement, and in this instance the construction of the joint is such that it consists of comparatively few parts for economy of construction and stability.

Other objects and advantages of my improved form of sectional plumb and level will be apparent from the following description, in connection with the accompanying drawing, and what I claim as new and desire to protect by Letters Patent is more specifically set forth in the appended claims.

In the drawing:

Fig. 1 is a side elevation illustrating the type of plumb and level to which my improved form of lap joint connection is applied.

Fig. 2 is an enlarged view with the sections partly separated—the end sections being partly broken away.

Fig. 3 is an end view of the center section of the plumb and level to illustrate face views of the securing means.

Fig. 4 is a sectional view of one of the attaching means for the joint.

Fig. 5 is a similar view of the companion attaching means, and

Figs. 6 and 7 are rear views of the plates forming part of the respective attaching means for the lap joints by which the sections are connected on a line with each other.

The joint in accordance with my invention is applied to the conventional type of plumb and level composed of three sections connected by lap joints and having the usual appurtenances such as shown in Fig. 1 of the drawing; that is bubble tubes to form a spirit level and grooves

5 to provide finger holds, as well as a hole near one end for suspending the implement from a nail when it is not in use. Consequently there is a center section 10 and opposite end sections 11 and 12, with the center section cut away at opposite ends to provide laps 13, 13 to cooperate with laps 14 of the end sections, and each lap joint is securely held together by the interlocking devices hereinafter described.

The connections at opposite ends of the center section are alike, and therefore a description of those at one end will apply to the others; that is to say, where the laps abut—at both their outer and inner ends—the interlocking devices for holding the sections of the implement together are the same.

In carrying out my invention I provide one of the parts of the joint with spaced apart prongs 15 projecting from a plate 16 on the center section of the implement to pass through corresponding holes in a companion plate 17 on the end section, each plate being let into the surface of the section to which it is applied so that when the sections are connected on a line with each other a close joint will be provided as illustrated in Fig. 1 of the drawing.

To secure the prong plate in place so that it may be adjusted with respect to the cooperating element of the connecting means said plate is provided with a rearwardly projecting boss 19 in the form of a nut engaged by a bolt 20 extending through the body of the center section 10 from the lower edge thereof—the boss being located in a recess 18 extending rearwardly from the shallow recess in which the plate is seated. As the prong plate is carried by the bolt its position is maintained against bodily outward movement of the bolt by means of a strong helical spring 21 interposed between the boss and bottom of the recess in which it is located, and of course vertical adjustment of the plate is effected by turning the bolt. The plate bears against the inner wall of the shallow recess surrounding recess 18, and this shallow recess is shaped to permit of vertical adjustment of the plate.

The companion plate 17 of the interlocking means is provided with holes 22 through which the prongs 15 pass when the parts of the lap joint are brought together, with aligning holes 23 in the section to which the plate is attached so that the prongs can project beyond the inner side of the plate, and in order to firmly hold the sections of the implement together the prongs engage a bow spring 24 seated in a correspond-

ingly shaped recess 25 in the back of the plate, for which purpose the prongs are provided with shallow notches engaged by the expansion of the spring as the prongs ride over the same. It will be noted that the notches are at the inner side of the prongs and shaped to permit the spring to yieldingly engage so that disengagement of the interlocking means may be effected by exerting a longitudinal pull on the sections of the implement, and that the ends of the prongs are rounded so that they may more easily enter the holes 22 in plate 17 when the sections are brought together. The plate receiving the prongs is secured in place by screws 26, two of which are located within the bow spring to not interfere with the functioning of the latter.

The edge of the implement opposite that near which the adjustable plate is located is provided with a recess and wear-plate 27 to receive the head of the bolt so that the latter will be within the straight edge—the plate preventing wear in the manipulation of the bolt—and as hereinbefore stated spring 21 holds the bolt and plate securely in place.

From the foregoing description it will be apparent that a sectional plumb and level provided with my improved form of interlocking devices can be easily manipulated in connecting the sections together when the implement is to be put to use, and as easily disconnected when desired, and that should the parts of either lap-joint not fit closely together this fault may be corrected by means of the adjusting bolt. Furthermore, it will be understood that a prong plate and adjusting bolt are provided at the inner end of the lap joint of each end section—as well as at the inner end of the lap joint of the center section—to cooperate with the keeper plates, and that the end sections of the implement are interchangeable.

I claim:

1. In a sectional plumb and level in which the sections are fitted together by lap joints, of means for holding the sections together including a plate attached to one of the sections and having prongs projecting therefrom, said prongs being notched at one side thereof, a keeper plate attached to the companion section and having holes through which the prongs project when the sections of the implement are brought together on a line with each other, and a spring in the rear of the keeper plate adapted to engage the notches in the prongs for yieldingly holding the sections together.

2. In a sectional plumb and level in which the sections are fitted together by lap joints, of means for holding the sections together including a plate attached to one of the sections and

having prongs projecting therefrom, said prongs being notched at one side thereof, a keeper plate attached to the companion section and having holes through which the prongs project when the sections of the implement are brought together on a line with each other, a bow spring in the rear of the keeper plate adapted to engage the notches in the prongs for yieldingly holding the sections together, and means for adjusting the prong plate to bring the lap joint together and thereby insure a close fit of the sections.

3. In a sectional plumb and level in which the sections are fitted together by lap joints, of means for holding the sections together, in accordance with claim 2, and in which the adjustment of the prong plate is effected by a bolt passing through the section of the implement to engage a threaded opening in the prong plate.

4. In a sectional plumb and level in which the sections are fitted together by lap joints, of means for holding the sections together including a plate attached to one of the sections and having prongs projecting therefrom, said prongs being notched at one side thereof, a keeper plate attached to the companion section and having holes through which the prongs project when the sections of the implement are brought together on a line with each other, a bow spring in the rear of the keeper plate adapted to engage the notches in the prongs for yieldingly holding the sections together, and means for adjusting the prong plate comprising a boss at the back of the plate in the form of a nut, a bolt extending through the section of the implement to engage the nut, and a spring exerting tension on the bolt to prevent bodily outward movement of the bolt.

5. In a sectional plumb and level in which the sections are fitted together by lap joints, of means for holding the sections together, on a line with each other including a plate attached to one of the sections and having prongs projecting therefrom, said prongs being notched at one side thereof, a keeper plate attached to the companion section and having holes through which the prongs project when the sections of the implement are brought together on a line with each other, means on the keeper plate for engaging the notches in the prongs when the joint is connected, and means for adjusting one of the plates comprising a rear projection having a threaded opening through the same, and a bolt extending through the body of the section of the implement and in engagement with the threaded opening in the projection for adjusting the plate in respect to engagement of the prongs.

THEODORE F. SEIWELL.
